UNITED STATES PATENT OFFICE.

JOHN L. HILL, OF TEXAS CITY, TEXAS.

SPARK-PLUG.

1,314,961.

Specification of Letters Patent.

Patented Sept. 2, 1919.

Application filed November 26, 1915. Serial No. 63,513.

To all whom it may concern:

Be it known that I, JOHN L. HILL, a citizen of the United States, residing at Texas City, in the county of Galveston and State 5 of Texas, have invented a new and useful Spark-Plug, of which the following is a specification.

My present invention relates to spark plugs, in which one electrode is movable 10 with respect to the other electrode or electrodes.

The principal object of my invention is to provide a spark plug which may, at all times, be maintained operative by the cleaning 15 of the sparking faces of the electrodes while the plug is in use.

Another object of the invention is to provide a plug whereby the intake and compression, and power and exhaust strokes of the 20 engine will reciprocate certain elements, one of which is an electrode, to effectively clean the electrodes after each ignition of the charge, thereby removing foreign matter from the sparking faces.

25 Other objects are to provide a spark plug which is inexpensive to manufacture and assemble; which will remain in good repair for a considerable length of time; and, which may be manually operated to demonstrate its practicability or to place the electrodes in sparking condition without removing the spark plug from the engine or rotating the engine shaft.

Other objects of the invention will appear 35 in the following detailed description, taken in connection with the accompanying drawing, forming a part of this specification, and in which drawing:

Figure 1 is a longitudinal sectional view 40 through a spark plug constructed according to my invention.

Fig. 2 is a view similar to Fig. 1, assuming that the plug has been given a quarter bodily turn.

45 Fig. 3 is a bottom plan view of the plug.

Fig. 4 is a sectional view on the line 4—4 of Fig. 2.

In the drawings, where similar characters refer to similar parts throughout the 50 several views, A designates an outer shell; B means for providing a bore C within, but insulated from the shell A; D reciprocal elements movable in said bore; and, E an element for cleaning one of the electrodes 55 and limiting the movement of elements D in one direction.

Referring first to the outer shell A, it is of the usual type, provided with a wrench head 5, screw headed portion 6 to be turned into the engine body, internal screw thread 60 7 within said wrench head and reduced internal bore 8 providing a shoulder 9.

Concerning the means B, in addition to comprising the usual body 10 of insulating material and the nut 11 having screw threaded engagement with thread 7, holding the enlargement 12 of body 10 firmly upon the shoulder 9, it includes a metallic sleeve 13 fitting within the bore 14 of body 10. The internal periphery of body 10 is enlarged as at 15, intermediate its ends, while the sleeve 13 is provided with an enlargement 16 fitting into the peripheral enlargement 15, as clearly shown in Figs. 1 and 2. This arrangement may be brought about by 70 forcing the sleeve 13 into the bore 14 of body 10 and expanding the lower end thereof so that the internal periphery of the enlargement 16 is aligned with the lower portion of the bore 14. By this construction a shoulder 17 is provided in sleeve 13 for the purpose hereinafter to be set forth.

The upper end of sleeve 13 preferably extends beyond the end of body 10 and is screw threaded as at 18, to receive nut 19, 85 and binding nut 20, between which may be secured a conductor of the ignition system.

As to the reciprocal elements D, they are 90 slidable within the bore C, and comprise a piston 21, slidable within the enlargement 16 of sleeve 13 and the lower portion of body 10; a stem 22 extending from piston 21, through the main body portion of sleeve 13 and exteriorly of the spark plug; and, a stem like electrode carried by and projecting from the other end of piston 21. If desired piston rings 24 may be provided about piston 21 and a suitable abutment 25 intermediate the 95 sparking face of the electrode 23 and piston 21. The piston 21 stem 22 and electrode 23 all have a common axis and it is to be observed that, by grasping the upper portion of stem 22 all of these elements may be reciprocated manually.

As to the element E, while I have shown 105 the spark plug as provided with two electrodes 26, either of which may co-act with the electrode 23 for providing a spark, and accordingly have disclosed element E as a U-shaped spider carried by the outer shell 110 A, it is to be understood that I do not wish myself limited to this particular construc-

tion, excepting in so far as the claims import. The electrodes 26 pass through perforations 27 in the upright arms 28 of the U-shaped spider, and may be of platinum 5 or other suitable material, secured in place as by sweating. The base 29 of the U-shaped spider is perforated at 30 and is spaced from the bottom of shell A at a distance sufficient to prevent its serving as an electrode when 10 the piston 21 is uppermost, yet it serves as a stop for movement of the piston in one direction, as by abutment 25 engaging the upper face of base 29. The perforation 30 is of such a size as to receive the electrode 23, 15 as piston 21 moves downwardly, and in this way, foreign matter is effectively removed from the sparking face of the electrode.

The sparking faces 31 of the electrodes 26 may be concave, as clearly shown in Fig. 20 4, and are alined with the internal wall of bore C so that, as piston 21 moves downwardly, and prior to the engagement of abutment 25 with base 29, any foreign matter 25 is wiped from the sparking faces 31 by the piston. Abutment 25 may be of such a length as to prevent the piston from moving sufficiently to expose the piston ring 24 which might permit it to expand.

The operation of the plug is as follows; 30 assuming that the lower face of piston 21 is in communication with the firing chamber of an internal combustion engine, when ever the engine is under compression, the piston is forced until its upper end engages abut- 35 ment 17, in which position the electrode 23 is in operative relation to the electrodes 26, however, during an intake stroke the piston 21 is moved toward element E, at times, augmented by the force of gravity, and the 40 electrodes are effectively cleaned of foreign matter, as hereinbefore described.

If desired, the upper portion of stem 22 may be grasped and a reciprocatory movement imparted to the other movable 45 elements, thereby effectively cleaning the electrodes or demonstrating the practicability of the invention, without operating the engine.

Changes in details may be made without 50 departing from the spirit of my invention; but,

I claim:

1. In a spark plug, the combination of an outer metallic shell, means rigid with said 55 outer shell providing a bore within but insulated from said outer shell, an electrode in conducting communication with said outer shell and having its sparking face in alinement with the inner face of the wall 60 of said bore, and a piston of substantially uniform diameter slidale in said bore, ac-

tuated by the intake and compression strokes of the engine, and having an amplitude of reciprocation sufficient to rub against the said sparking face thereby wiping foreign 65 matter from the said face during reciprocation of the piston.

2. A sparking plug comprising in combination, an outer shell provided with a perforated U-shaped spider at its lower end, 70 means providing a bore within but insulated from said outer shell, axially alined with the said perforations, electrodes carried by the upright arms of said spider, disposed with their sparking faces alined with the inner 75 face of the wall of said bore, a piston in said bore having an amplitude of reciprocation sufficient to rub against the said sparking faces, and an electrode coaxial and movable with said piston disposed to 80 extend through the said perforations in the said spider during movement of said piston toward said spider, said last mentioned electrode of a diameter relative to the diameter of said perforations, so as to come in wiping 85 engagement with said spider at its circumferential face.

3. A spark plug comprising in combination, an outer shell, a body of insulating material carried by said shell and having 90 a bore with its internal periphery enlarged intermediate the ends, a sleeve of conducting material within said bore having an enlargement embedded in said peripheral enlargement, the bore of said sleeve at said 95 enlargement thereof being alined with the bore of said body, a piston slidale in the bores of said sleeve enlargement and body, a stem extending from one end of said piston through said sleeve and exteriorly of 100 said body and outer shell, an electrode at the opposite end of said piston, an electrode carried by said shell, and an element carried by said shell having a perforation in which said first mentioned electrode may 105 move upon reciprocation of said piston, substantially as and for the purpose set forth.

4. A spark plug comprising in combination, an outer metallic shell, a plurality of stationary electrodes in conducting communication therewith, a movable electrode, means permitting movement of said last mentioned electrode into and out of sparking relation to said stationary electrodes, including an element adapted to wipe the 110 115 sparking faces of the latter when said movable electrode is moved out of sparking relation to said stationary electrodes, and means for wiping the portions of said movable electrode which confront said stationary 120 electrodes.
